Primary Examiner—Janice E. Seeger*Assistant Examiner*—Sydney R. Buffallow(74) *Attorney, Agent, or Firm*—Cahill, von Hellens & Glazer P.L.C.(57) **CLAIM**

The ornamental design for a card holder, as shown and described.

DESCRIPTION

FIG. 1 is an isometric view from the front, left and top of a card holder showing my new design, the broken lines depicting a card partially inserted form no part of my design; FIG. 2 is an isometric view taken from the rear, left and top thereof; and,

FIG. 3 is a right elevational view thereof, the left elevational view being a mirror image.
